UNITED STATES PATENT OFFICE.

ROY DOUGLAS CONWAY, OF CHATHAM, NEW JERSEY, ASSIGNOR TO WESTERN ELECTRIC COMPANY, INCORPORATED, OF NEW YORK, N. Y., A CORPORATION OF NEW YORK.

COIN-COLLECT SYSTEM FOR AUTOMATIC TELEPHONE EXCHANGES.

Application filed August 11, 1920. Serial No. 402,760.

To all whom it may concern:

Be it known that I, Roy D. Conway, a citizen of United States, residing at Chatham, in the county of Morris, State of New Jersey, have invented certain new and useful Improvements in Coin-Collect Systems for Automatic Telephone Exchanges, of which the following is a full, clear, concise, and exact description.

10 This invention relates to machine switching telephone systems with subscriber's control wherein coin collectors are provided at the substations.

15 Its object is to provide an improved circuit arrangement for systems of this type which shall be positive and efficient in operation.

One feature of this invention is the provision of improved means for preventing a 20 calling party from building up a connection until he has deposited a coin in the coin box. In accordance with this feature, a marginal relay is provided at the central office which does not operate upon the mere closure of 25 the loop by the removal of the receiver at the calling station, but only operates due to a circuit change which is caused by the deposit of a coin in the coin box. In the present embodiment this relay is included in a 30 circuit including the free pole of the battery at the central office one side of the line, the substation loop, the other side of the line and a high resistance at the central office to ground. When the ground branch is closed 35 at the calling substation by the deposit of the coin, this high resistance return is shunted and the marginal relay thereupon operates. In operating it connects the impulse 40 relay to the one side of the calling line and causes said high resistance in the other side to be permanently shunted by a direct ground return. This impulse relay in operating closes a bridge of the talking conductors to and including the impulse relay of 45 the first selector. Thus the stepping mechanism of the first selector is placed under control of the calling subscriber's dial, who may now proceed to build up his connection.

The present circuit arrangement makes 50 possible the employment in pure automatic working of the coin box shown in Forsberg Patent No. 1,043,219, dated Nov. 5, 1912 which is now in general and successful use in manual working in the Bell system, with-

out changing the design of the coin box in 55 any way.

Coin collect circuit arrangements are known wherein the calling party cannot build up a connection without depositing a 60 coin in the box, but in these systems, additional contacts had to be provided in the coin box to short circuit the sender impulse springs. It is desirable from an operating standpoint to reduce the work the coin must do as far as possible. The work the weight 65 of a ten cent piece can do for example is very small. This coin, however, satisfactorily operates the springs of the coin box patent referred to.

Another feature consists in the provision 70 of improved means for preventing the discharge of the condensers in the connecting circuit from interfering with the character of the impulses transmitted to the stepping magnets of the switches.

A further feature relates to the provision 75 of a circuit arrangement for systems of the character which will take care of free calls as well as ordinary calls.

Another feature consists in the provision 80 of a circuit arrangement for pure automatic working wherein the deposit of the coin connects the polarized magnet in the coin box to ground, for preventing this ground from holding up the release of the switches when 85 the subscribers replace their receivers.

Referring to the drawings Fig. 1 shows a calling line, a line switch and the coin control circuit; Fig. 2 shows a secondary line switch, a first selector, a connector and the 90 called line.

The invention will be most readily understood from a detailed description of the operations involved in setting up a connection.

Upon the removal of the receiver at the 95 calling substation, the relay 101 of the primary line switch PLS individual to the calling line is operated over the calling line circuit. In attracting its armature it closes a circuit including the pull down winding 100 102 of the line switch which causes the line switch to seize the preselected trunk by operating the set of springs in the well known manner, as shown and particularly described for example in Patent No. 1,304,369, 105 to A. J. Ray of May 20, 1919. The calling line is now extended to the trunk circuit, whereupon relay L is operated as follows:

free pole of battery, contact 104 of relay Y, conductor 105, contact 106 of relay S', conductor 107, contact 108 of relay N N, resistance 187, conductors 109, 110, the inner right armature and back contact of relay B, lower armature and back contact of relay A, ring conductor 165 including contacts 162, 163 of the line switch, the telephonic loop at the calling substation, tip conductor 164, including springs 166, 167 of the line switch, upper armature and back contact of relay A, left armature and back contact of relay B, retardation coil 188, relay L, outer left armature and back contact of relay N N to ground. Relay L closes a circuit for the cut-off winding 103 of the line switch to hold the line switch set before the circuit for the pull down winding 102 is opened as the line relay 101 releases. The circuit for the cut-off winding is as follows: ground, left armature and front contact of relay L, conductor 131, outer right armature and back contact of relay H H, conductor 199, contact 198 of relay N N, conductor 146, release or sleeve conductor 125, springs 112, 113, cut-off winding 103, free pole of battery.

When the primary line switch PLS operated and closed springs 114, 115 the following circuit was closed to operate the secondary line switch SLS to seize an idle first selector; grounded spring 115, spring 114, secondary line switch holding conductor 116, outer left armature and back contact of relay H H, conductor 117, conductors 201, 202, pull down coil 203 of the secondary line switch, contact 204, conductor 205, slow relay 206, to free pole of battery. The secondary line switch SLS in operating closes a locking circuit for itself, including its windings 207, 203 in series and contact 208, to grounded holding conductor 201.

Relay L, in attracting its left armature, operates slow to release relay N, which operates relay N N. Relay N N in attracting its outer left armature removes the shunt from about the high resistance 118 for a purpose which will shortly appear, and in attracting its inner left armature grounds the release conductor 125 over conductor 146 to hold up the primary switch PLS after relay L releases.

Relay N N in attracting its inner right armature at 108 substitutes relay RT for resistance 187 in the calling line circuit. Relay RT is thus connected to the ring side 165 of the calling line.

Relay RT is marginal and will not operate over the line circuit due to the high resistance 118 and relay L. Resistance 118 is normally short circuited, its short circuit being removed when relay N N operates to increase the margin of operation of relay RT.

The circuit remains in this condition until

the calling party inserts a coin in the coin box. The coin box may be of the type shown and described in the said Forsberg patent. As shown and described in detail in said patent, the deposited coin causes the closure of contact 120 to ground the tip side of the line 164 and since the receiver is now removed from its hook, this ground is also connected to the ring-side of the line 165. The application of this ground closes a shunt about relay L and the high resistance 118, whereupon the marginal relay RT operates over a circuit including the ring side of the line 165, the calling substation receiver hook, and the ground closed by contact 120 of the coin box.

Relay RT in operating, energizes relay S' over the following circuit: battery, armature and front contact of relay RT, conductor 121, relay S', conductors 122, 123, outer left armature and front contact of relay N N to ground. In attracting its outer left armature, relay S' connects conductor 116 to conductor 117 independently of the outer left armature and back contact of relay H H. In attracting its middle left armature, relay S' provides a direct path to ground through coil 188 from the tip side 164 of the line short circuiting relay L and resistance 118. Relay L releasing, opens the circuit of relay N which is slow to release. In attracting its inner left armature, relay S' connects the impulse relay R' to the ring side 165 of the line. In attracting its inner right armature it removes relay RT from the calling line circuit and locks itself to grounded battery at a normal contact of relay Y and to the grounded sleeve or release conductor 124. This conductor was grounded when the secondary line switch seized the first selector in the well-known manner. The locking circuit of relay S' is as follows: free pole of battery contact 104 of relay Y, conductor 105, inner right armature and front contact of relay S', relay S', conductor 122, grounded sleeve wire 124. In attracting its outer right armature, it operates relay H H and slow relay H. The circuit for relay H H leads over conductor 176 and the outer right armature of relay B and conductor 189. Relay H then locks itself over conductors 174, 176, outer right armature and back contact of relay B, conductor 189, to battery at its own armature and front contact. Relay H H being connected to conductor 189 is also held up by the armature of relay H.

Relay H H in attracting its inner right armature, connects grounded conductor 148 over conductor 147 to the release conductor 125, leading back to the primary line switch to maintain the cut-off winding 103 thereof energized independently of the ground supplied at the inner left armature of relay N N, which relay releases when slow relay

5 N releases, the circuit of relay N having been opened as relay L was short circuited when relay S' operated. The grounded conductor 148 is however extended to the sleeve conductor 125 by relay H H before relay N, which is slow, releases.

10 The calling party now operates his sender in accordance with the first digit of the wanted number, and on the return of the sender to its normal position, the following 15 circuit including the impulse relay R' is interrupted: free pole of battery, relay R' conductor 126, inner left armature and front contact of relay S', conductors 127, 128, inner right armature and back contact of relay B, lower contacts of relay A, the ring side 165 of the line, the substation loop, the tip side 164 of the line, the upper back contacts of relay A, left armature and back contact of relay B, retardation coil 188 to ground at the middle left armature of relay S'. The ground connected to the tip side of the line at springs 120 does not interfere with this impulse circuit. Upon 20 initial operation of relay R' before the sender was operated, it closed at its lower front contact a circuit for slow-to-operate relay D which in operating extended the front contact of relay R' to energize relay D D 25 which connected the incoming and outgoing ends of the tip and ring conductors together, these conductors including a pair of condensers 129, 130. Upon the first retraction of the armature of impulse relay R', due to 30 the sender interrupting the line, relay D D instantly retracts its armatures, disconnecting the incoming tip and ring conductors from the outgoing tip and ring conductors. Relay D is constructed and arranged so 35 that it will not again attract its armature while the impulse relay armature is vibrating. Relay D D thus remains inert during this period to maintain the condensers disconnected from the outgoing ends of the tip and ring conductors to prevent interference with the character of the impulses, by 40 the discharge of the condensers.

45 Only parts of the switches S and C are shown, since these switches are well known. 50 They may be of the type shown in Reissue Patent No. 13901, issued April 13, 1915 to F. Newforth, Jr.

55 Assuming that the selector S and preceding switches have been set and the calling line extended to the connector C, the impulse relay 210 (Fig. 2) of the connector C is operated over the following circuit: free pole of battery, right winding of relay 210, normal contact of relay 211, conductor 233, 60 ring conductor 212, multiple terminal 213 and brush 214 of the selector S, ring conductor 215, secondary line switch contact 216, ring conductor 232, conductor 132, (Fig. 1) contact 133 of relay J, conductor 134, upper armature and front contact of

relay R', conductor 135, conductor 136, contact 137 of relay D D, conductor 138, polarized relay P, tip conductor 139, contact 140 of relay J, conductor 194, tip conductor 225, contact 226, tip conductor 227, brush 228, terminal 229 of selector S, tip conductor 230, conductor 231, outer normal contact of relay 211, left winding of relay 210 to ground. Relay 210 at its front contact operates slow relay 240, which interposes a break in the circuit of release magnet 241 and grounds the sleeve wire 245 in the well-known manner.

70 The operations of setting the connector need not be described since they are well known and form no part of this invention. The impulse relay R', which is in circuit with the sender, at its upper armature and front contact controls the circuit of the connector impulse relay 210.

75 When the connection has been built up to the called line, the response of the called party operates relay 211 which reverses the flow of current in the tip and ring conductors leading back to the coin collect circuit. Relay P, which is polarized, thereupon operates, closing a circuit for relay C to prepare a circuit including the coin collect source C C and the calling line. The circuit for relay C is as follows: free pole of 80 battery, relay C and its normal upper contact, conductor 142, armature and contact of relay P, conductors 192, 157, 146 to the release conductor 125, which is grounded at the inner right armature of relay H H. Relay C 85 in attracting its armature 155 locks itself to conductor 146. Relay J is also energized over the following circuit due to the operation of relay P: free pole of battery, resistance 184, relay J, conductor 150, armature of relay K, conductor 142, contact and armature of relay P, conductors 192, 157, 146, to ground over the path traced for relay C. Relay J locks itself over its armature 152, conductors 151, 157, to grounded conductor 146, as previously traced. Relay J 90 reverses the connection of the tip and ring conductors 194 and 132 with the tip and ring conductors 139, 134 for a purpose which will appear later. Relay C in operating, 95 closes the following circuit for relay A: free pole of battery, relay A, conductor 154, uppermost armature and front contact of relay C, to the grounded sleeve conductor 124. Relay A extends the tip and ring conductors leading from the primary line switch to the tip and ring conductors 139, 134, cutting off the bridge containing the impulse relay R' and retardation coil 188. Relay R' in releasing its upper armature removes the bridge containing the impedance coil 181 from across the talking conductors.

100 The subscribers may now converse. Talking current is fed from the connector to the calling line over the following circuit: free 105 pole of battery, conductor 154, tip conductor 139, 134, ring conductor 132, conductor 133, contact 134, upper armature and front contact of relay R', conductor 135, conductor 136, contact 137 of relay D D, conductor 138, polarized relay P, tip conductor 139, contact 140 of relay J, conductor 194, tip conductor 225, contact 226, tip conductor 227, brush 228, terminal 229 of selector S, tip conductor 230, conductor 231, outer normal contact of relay 211, left winding of relay 210 to ground. Relay 210 at its front contact operates slow relay 240, which interposes a break in the circuit of release magnet 241 and grounds the sleeve wire 245 in the well-known manner.

10 pole of battery, right winding of relay 210, outer armature and front contact of relay 211, conductors 231, 230, terminal 229, brush 228, conductor 227, contact 226, conductor 225, contact 159 of relay J, conductors 134, 160, 161, lower armature and front contact of relay A, contact springs 162, 163, conductor 165, through the substation talk-set, conductor 164, spring 166, 167, conductor 164, 165 upper armature and front contact of relay A, conductor 168, relay P, conductors 139, 170, armature 169 and front contact of relay J, conductor 132, conductor 232, contact 216, conductor 215, brush 214, terminal 213, conductors 212, 233, inner armature and front contact of relay 211, left winding of relay 210 to ground. Current is fed to the called line over the windings of relay 211.

20 When the calling party replaces his receiver, ground is removed from the sleeve conductor 245 by the release of slow relay 240, which causes the connector and selectors to restore. The removal of this ground also releases relay S', which in releasing its 25 outer left armature releases the secondary line switch SLS. Relay S' at its outer right armature and back contact also closes a circuit for relay Y as follows: free pole of battery, outer right armature and back contact 30 of relay S', conductor 171, relay Y, contact 172 of said relay, conductor 173, inner left armature of relay H H, lower contact of the constantly operating interrupting machine I to ground, when the lower contact is closed 35 by the cam of the machine. Relay Y in operating, locks itself to grounded conductor 148 by closing its contact 177.

40 When the interrupting machine I next closes its upper contact, an impulse of current is delivered to coin current applying relay B over the inner left armature and front contact of relay Y. This relay in attracting its armature impresses positive current of preferably 110 volts from the collect 45 source C C to the calling line to operate the polarized magnet PR in the coin box at the calling station to collect the coin. This circuit is as follows: free pole of source C C, conductor 178, lower armature and front 50 contact of relay C, relay 190, conductor 179, left armature and front contact of relay B, upper armature and back contact of relay A, springs 167, 166, tip conductor 164, contact 120, polarized magnet PR to ground. Relay 55 A released when ground was removed from the sleeve conductor at the connector. The polarized magnet PR operates to collect the coin as shown and described in said Forsberg patent. In operating, magnet PR locks 60 itself to ground by closing contact 119 and then releases the coin, opening contact 120. Due to the closure of contact 119, the magnet PR remains operated as long as the coin current is applied, as shown and described in detail 65 in said Forsberg patent. In case the first

70 impulse from the interrupting machine fails to cause the collection of the coin, additional impulses are sent and the release of the primary line switch PLS is held up in the following manner:

75 When the relay B operated, in attracting its outer armature it opened the locking circuit previously traced for slow relay H, but before the relay H can de-energize, a substitute circuit is closed by the armature of relay 190 which operates in the coin current circuit in series with the polarized magnet PR. Relay H as pointed out holds up relay H H which at its inner right armature is maintaining ground on the sleeve conductor leading to the holding winding 103 of the primary line switch. Thus these two alternate circuits maintain relay H operated until the ground at the substation is removed. 80 As long as relay Y remains operated, lamp 85 180 lights before an attendant, who will investigate in case the apparatus does not function properly.

90 Assuming, as in the normal case, that the polarized magnet PR functions properly, the second time the relay B operates from the interrupter I no ground will be present at the substation and the relay 190 will fail to operate and the substitute circuit for relay H at the front contact of relay 190 will 95 not be present when relay B opens the other circuit at its outer right armature and back contact when it is next operated from the interrupter I. Relay H accordingly releases, releasing relay H H. Relay H H in 100 retracting its inner right armature removes ground from the sleeve conductor leading to the holding winding 103 to the line switch, resulting in the release of the same.

105 In case the called party has not responded, polarized relay P would not have shifted its armature and relay C would have remained inert. At its lower armature, this relay would have connected negative current from the 110 volt coin return source CR to the calling line to cause the polarized magnet PR to refund the coin, lock up to ground at contact 196, and open contact 120. When the operating current ceases, magnet PR releases, opening contact 196 whereupon the primary line switch would release as described. 110

115 Certain lines called free lines are segregated upon connectors which do not reverse the current flow in the calling line when the called party responds. On such calls, battery is fed to the calling line over the impulse circuit previously traced, the relay R being balanced by the retardation coil 188, the condensers 129, 130 separating the calling and called ends of the circuit. 120

125 The retardation coil 181 is provided in these calls to prevent short-circuiting the voice currents.

130 Upon disconnection in this class of calls,

inasmuch as relay C is not operated, the coin is refunded as in the case of unsuccessful calls.

Resistance 182 is connected to ground at one end and to the condensers 129, 130 at the other end over normal contacts of relay DD. The other terminals of these condensers are connected over normal contacts of relay A to the armatures of relay B over which the relatively high potential coin current flows. This arrangement is for preventing the burning of the contacts of relay B when the high voltage coin current is cut off by the interrupter I releasing relay B.

The ground applied by the polarized magnet PR is connected to the tip side 164 of the line and the ground through the relay 210 at the connector is also normally applied to the same side of the line. However, when the relay 211 is operated when the called party answers, battery is connected to the tip side of the line and to prevent this change from affecting the release operation, relay J which operates due to relay 211 operating is provided to restore the original connections.

More particularly, when the calling party is the first to replace the receiver, inasmuch as relay J is locked to ground on the release conductor 125, the holding circuit for relay 210 through its right winding to the coin ground, will be opened at the switchhook contacts 100 of the calling substation. Relay 210 therefore releases, opening the circuit of the usual slow relay 240. The release of the slow relay energizes the release magnet 241 which releases the connector and the release of the slow relay removes ground from the sleeve conductor 235, which releases the selectors. The selectors release before the coin collecting operations are completed and inasmuch as the ground on the release wire 125, to which relay J is locked, cannot be removed until these operations are completed the circuit referred to from the ground in the coin box to the right winding of relay 210 is not closed.

When the called party restores first, relay 211 releases and reverses the current flow in the calling line. In this event relays J and K cooperate to prevent this condition from affecting release. When the relay J operated upon the response of the called party, it caused relay P to restore and closed a circuit for relay K by attracting its armature 183 this circuit including the grounded sleeve wire 125. Relay K at its right armature in operating prepares a circuit to shunt relay J. When the called party replaces his receiver and reverses the current flow in the calling line, relay P operates and shunts out relay J over resistance 184, conductor 185, armature and front contact of relay K, contact of relay P, conductors 192, 157, 146, 147, inner right armature of relay H H to grounded conductor 148. Relay P releases

before relay K closes its back contact, thus preventing relay J from again operating. Relay J restores the original connections to the tip and ring conductors so that the ground in the coin box is now connected to the tip side 164 of the line to which the grounded side of relay 210 is connected. Thus when the calling party restores his receiver, no circuit could be maintained closed from the coin ground to the winding of relay 210 to which the free pole of battery is connected. Thus release is not prevented.

Relay P is located in the tip side of the line rather than the ring side so that if the called party hangs up immediately after the calling party and releases relay 211 thus reversing battery to the calling party before the slow relay in the connector has time to release and remove the ground from the sleeve wire which is holding up relay S', relay P will be operated when relay 211 releases over a circuit from the free pole of battery through right winding of relay 210 to the coin ground, thus shortcircuiting relay J as described, which reconnects the coin ground to the grounded side of relay 210 and reconnects the side of relay 210 connected to the free pole of battery to the ring side of the line which is open at the switchhook. Thus release is not interfered with.

Certain levels of the selector S or a preceding selector may contain trunks leading to operator's positions, such as information or toll operators. The induction coil 186 is provided to give such operators a tone to inform them of the character of the line. As shown in British patent No. 15133 of 1911, tone may be induced in the secondary 197 of the induction coil 195 from a class tone source CT which is transmitted by a coil 186 to the sleeve wires 124, 235, 237 and thence to the operator's head set, as shown and described in said patent.

What is claimed is:

1. In a machine switching telephone exchange system, the combination of calling and called telephone lines, connecting circuits including numerical and non-numerical automatic switches, means automatically operated by the removal of the receiver at the substation associated with any one of the calling lines for causing said non-numerical switches to operate and extend the particular calling line to an idle connecting circuit, a coin collector at the calling substation having a magnet to collect or refund a deposited coin, means operated by the deposit of a coin in said collector for bringing about a circuit change in the substation equipment, a test relay in the connecting circuit at the central office operated in response to such circuit change, a control circuit for said automatic switches, a contact therein, an impulse relay for closing said contact operated over the calling line by the energi-

zation of said test relay, and a sender at the calling substation for operating said impulse relay to control the setting of said numerical switches.

5. 2. In a machine switching telephone exchange system, the combination of calling and called telephone lines, connecting circuits including numerical and non-numerical automatic switches, means automatically operated by the removal of the receiver at the substation associated with any one of the calling lines for causing said non-numerical switches to operate and extend the particular calling line to an idle connecting circuit, a coin collector at the calling substation having a coin disposal magnet, means operated by the deposit of a coin in said collector for connecting said magnet to ground from one side of the line, a test relay in the connecting circuit at the central office operated in response to such grounding of the line, a control circuit for said automatic switches, a contact therein, an impulse relay for closing said contact operated over the calling line by the energization of said test relay, and a sender at the calling substation for operating said impulse relay to control the setting of said numerical switches.

3. In a machine switching telephone exchange system, the combination of calling and called telephone lines, connecting circuits including numerical and non-numerical automatic switches, means automatically operated by the removal of the receiver at the substation associated with any one of the calling lines for causing said non-numerical switches to operate and extend the particular calling line to an idle connecting circuit, a coin collector at the calling substation having a polarized magnet, a relay L at the central office operated over the calling line circuit, a relay N N operated by said relay, a test relay connected to the calling line by said relay N N, a switch in said coin collector operated by the deposit of a coin for connecting said test relay to ground from one side of the line, an impulse relay connected to the calling line loop by said test relay, an impulse circuit for said numerical switches including a contact closed by said impulse relay, and a relay operated by said test relay for shunting said relay L.

4. In a machine switching telephone exchange system, the combination of a calling and a called line, connecting circuits including numerical and non-numerical automatic switches, means automatically operated by the removal of the receiver at the substation associated with the calling line for causing said non-numerical switches to operate and extend the calling line to an idle connecting circuit, a coin collector at the calling substation having a magnet for disposing of the deposited coin, means operated by the

deposit of the coin for connecting said magnet to ground from one side of the line, a supervisory relay 211 in the final numerical switch circuit operated upon the response of the called party for reversing the calling line battery connections, thereby connecting the grounded side of said line to the same talking conductor of the final numerical switch as that to which the free pole of the battery is connected, a polarized relay P in series with the calling line operated upon this current reversal, and a second current-reversing relay J operated by the polarized relay to again reverse the current flow in the calling line, thereby reconnecting the grounded side of said line to the talking conductor to which the grounded pole of the battery is connected in the final numerical switch circuit.

5. In a machine switching telephone exchange system, the combination of a calling and a called line, connecting circuits including numerical and non-numerical automatic switches, means automatically operated by the removal of the receiver at the substation associated with the calling line for causing said non-numerical switches to operate and extend the calling line to an idle connecting circuit, a coin collector at the calling substation having a polarized magnet, means operated by the deposit of a coin for connecting said magnet from one side of the line to ground, a reversing relay in the final numerical switch circuit operated upon the response of the called party, thereby connecting the grounded side of said line to the same talking conductor of the final numerical switch as that to which the free pole of the battery is connected, a calling supervisory and battery feeding relay 210 in the final numerical switch circuit associative with and controlled by the calling line, a polarized relay in series with the calling line circuit, a reversing relay J operated by the polarized relay for again reversing the battery feeder connections to the calling line, thereby again connecting the grounded side of said line to that side of the talking circuit which is connected to ground in the final numerical switch circuit, a release circuit for said switches controlled by the calling supervisory relay 210 in the final numerical switch circuit, and means for holding said second reversing relay J operated until the switches release.

6. In a machine switching telephone exchange system, the combination of calling and called telephone lines, connecting circuits including numerical and non-numerical automatic switches, means automatically operated by the removal of the receiver at the substation associated with any calling line for causing said non-numerical switches to operate and extend the particular calling line to an idle connecting circuit, a bridge

- across the connecting circuit preceding said numerical switches and including an impulse relay and the calling line, a coin box at the calling station including a polarized magnet, sources of current of different polarity at the central office, means at the central office, operated after the called party responds, to disconnect said bridge and extend the calling line to the final numerical switch circuit and prepare a circuit including one of said current sources and the calling line, means operated by the opening of the calling line circuit for closing said prepared circuit to operate said polarized magnet to collect 5 the coin, said bridge disconnecting means not being operated when the final numerical switch selects free lines, a source of talking current connected to the calling line over said bridge, and means operated by the restoration of the calling party's receiver for connecting the other source to the calling line to operate said polarized magnet to refund the coin.
7. In a machine switching telephone exchange system, the combination of calling and called telephone lines, connecting circuits including numerical switches, a coin collector at the substation associated with any one of the calling lines having a magnet to collect or refund a deposited coin, means operated by the deposit of a coin in said collector for bringing about a circuit change in the substation equipment, a test relay in the connecting circuit at the central office operated in response to such circuit change, a stepping circuit including a contact of said relay and the impulse relay of the first numerical switch, a sender at the calling substation for intermittently operating said impulse relay to control the setting of said switch and the succeeding switches to build up a connection to a called line, and means operated subsequent to the response of the called party for impressing current 25 on the calling line to cause said magnet to collect the deposited coin.
8. In a machine switching telephone exchange system, the combination of calling and called telephone lines, a train of connecting circuits including numerical and non-numerical automatic switches, means automatically operated by the removal of the receiver at the substation associated with any one of the calling lines for causing the non-numerical switches to operate and extend the calling line to an idle numerical switch circuit, a coin collector at the calling substation having a magnet to collect or refund a deposited coin, means operated by the deposit of a coin in said collector for bringing about a circuit change in the substation equipment, a test relay in one of the connecting circuits in the train of connecting circuits at the central office operated in response to such circuit change, a control cir- 30
- cuit for said automatic switches, a contact therein, an impulse relay controlled by the operation of said test relay for closing said contact, a sender at the calling substation for operating said impulse relay to control the setting of said switches, sources of current of different character at the central office, and means operative upon the breaking down of the connection and dependent upon whether or not the called subscriber has responded for impressing current from the proper source to operate said magnet to dispose of the coin.
9. In a telephone system, telephone lines, a connecting circuit including a line switch and a first selector, means operated by the removal of the receiver of the calling station for operating said line switch to extend the calling line to said first selector, a circuit including a marginal relay, said line and a high resistance, a coin collector at said calling station having a magnet, means operated by the deposit of a coin in said coin collector for connecting said magnet to ground to shunt said high resistance to operate said marginal relay, an impulse circuit for setting said selector, a dial at the substation, means controlled by said marginal relay in operating for placing said impulse circuit under control of said dial, and means for impressing current on the calling line to operate said coin collector magnet to dispose of the deposited coin.
10. In a telephone system, telephone lines, a connecting circuit including a line switch and a first selector, means operated by the removal of the receiver of the calling station for operating said line switch to extend the calling line to said first selector, a circuit including a marginal relay at the central office, said line and a high resistance, a coin collector at said calling station having a magnet, means operated by the deposit of a coin in said coin collector for connecting said magnet to ground to shunt said high resistance to operate said marginal relay, an impulse relay, an impulse circuit for setting said selector controlled by said impulse relay, a dial at the substation, means controlled by said marginal relay in operating for connecting said impulse relay to the calling line in circuit with said dial and for removing said marginal relay from connection with the calling line, and means for impressing current on said calling line to operate said magnet to collect or refund the deposited coin.
11. In a telephone system, a calling telephone line, a sender and a coin collector at the sub-station thereof, a central office in which said line terminates, an automatic numerical switch therewith, an impulse circuit for controlling the same, a circuit including an electromagnetic responsive device

at the central office and said line closed upon the initiation of a call, means actuated by the deposit of a coin in said coin collector for altering the electrical condition of said latter circuit, said device being responsive to said change to place said impulse circuit under the control of said substation sender, and means for subsequently impressing current on said calling line to operate said coin collector to dispose of the deposited coin.

12. In a telephone system, a calling telephone line, a sender and a call charging means at the substation thereof, a central office in which said line terminates, automatic numerical switches thereat, an impulse circuit for controlling the same, a circuit including an electromagnetic responsive device at the central office and said line closed upon the initiation of a call, means operated by the actuation of said call charging means for changing the electrical condition of said latter circuit, said device being responsive to said change to place said impulse circuit under the control of said substation sender, and means for subsequently impressing current on said calling line to operate said call charging means.

13. In a telephone system, a calling telephone line, a sender and a coin box at the substation thereof, a central office in which said line terminates, an automatic numerical switch thereat, an impulse circuit for controlling the same, means actuated by the initiation of a call for automatically extending the calling line to said switch, means operated by the deposit of a coin in said coin box to ground one side of the calling line, a test relay at the central office operated in response to the grounding of said line for placing said impulse circuit under the control of the substation sender, and means for subsequently impressing current on said calling line to operate said coin box to dispose of the deposited coin.

14. In a telephone system, a calling line, a sender and call charging mechanism at the substation thereof, a central office in which said line terminates, an automatic numerical switch thereat, an impulse circuit for setting said switch, means actuated by the initiation of a call for extending the calling line to said switch, means operated by the actuation of said call charging mechanism for altering the substation circuit, a test relay at the central office responsive to such alteration for placing said impulse circuit under the control of the substation sender, and means for subsequently impressing current on said calling line to operate said call charging mechanism.

15. In a telephone system, a calling line, a sender and a coin collector at the substation thereof, a central office in which said calling line terminates, automatic switches

at said central office, a circuit for actuating one of said switches closed upon the initiation of a call, an impulse circuit for controlling the remaining switches, a circuit including a test relay at the central office and said calling line closed upon the operation of said automatic switch, means for altering said circuit actuated by the deposit of a coin, said test relay being responsive to said altered condition to place said impulse circuit under the control of said substation sender, and means for subsequently impressing current on said calling line to operate said coin collector to dispose of the deposited coin.

16. In a telephone system, a calling line, a dial and a coin box at the substation thereof, a central office in which said calling line terminates, a series of numerical switches thereat, an impulse circuit therefor, a line switch adapted upon the initiation of a call to extend the calling line to the first of said numerical switches, means operated by the deposit of a coin in the coin box for grounding one side of the line, a test relay at the central office responsive thereto for placing said impulse circuit under the control of the substation dial, and means for automatically selectively disposing of the deposited coin upon the breaking down of the connection.

17. In a machine switching telephone exchange system, the combination of calling and called telephone lines, connecting circuits including numerical and non-numerical automatic switches, means automatically operated by the removal of the receivers at the calling stations for causing said non-numerical switches to operate and extend calling lines to idle connecting circuits, call charging mechanism at the calling substations, senders at the calling substations, and marginal electromagnetic means at the central office under the control of said call charging mechanism for rendering said numerical switches responsive to said senders.

18. In a machine switching telephone exchange system, the combination of calling and called telephone lines, automatic switching mechanism for interconnecting said lines, call charging mechanism at the calling substation, means controlled by an operation of said charging mechanism for altering the circuit of the substation, a control circuit for said switching mechanism, marginal means at the central office operated in response to such circuit change to govern said control circuit, and a sender at the calling substation for operating said governing means to control the setting of said switching mechanism.

In witness whereof, I hereunto subscribe my name this 7th day of August A. D., 1920.

ROY DOUGLAS CONWAY.
